UNITED STATES PATENT OFFICE.

AUGUST MARIUS KJAERSGAARD, OF CORINTH, DENMARK, ASSIGNOR, BY MESNE ASSIGNMENTS, TO THE FIRM OF HANNEFORDS, LIMITED, OF LONDON, ENGLAND.

REFRIGERATOR.

1,129,991.

Specification of Letters Patent.

Patented Mar. 2, 1915.

Application filed March 4, 1912. Serial No. 681,483.

To all whom it may concern:

Be it known that I, AUGUST MARIUS KJAERSGAARD, citizen of the Kingdom of Denmark, and a resident of the village of Corinth, county of Fyen, Denmark, engineer, have invented a new and useful Improvement in Refrigerators of that Type in which the Cooling Action is Effectuated by Vaporizing a Volatile Liquid and then Absorbing the Vapor.

The following is a specification describing the device.

The invention relates to a refrigerator, especially adapted for domestic purposes and wherein a relatively low temperature is obtained by the vaporization of a fluid in a vessel inclosed in a compartment of the refrigerator.

An object of the invention is to maintain for a long period a relatively low temperature by supporting the container in a fluid which is non-congealable and which is refrigerated by the low temperature in the container.

Another object of the invention is to provide a device for communicating the reduced temperature of the container to the entire compartment wherein the container holding the fluid to be evaporated is supported.

With these and other objects in view I have illustrated an embodiment of the invention in the accompanying drawing.

Figure 1 shows a refrigerator in front elevation. Fig. 2 is a side view of the compartment holding the container.

The refrigerator shown in the accompanying drawing as a cabinet 1, contains a compartment 2, in which a container 3 is located. A plurality of pipes 4 extend from this container 3 and return to the same for the purposes described below. The container 3 may contain water or some other fluid vaporized by evacuation and the compartment 2 may be filled with brine or the like. A pipe 5 extending from the container 3 through the top of the refrigerator is connected with a pipe which leads into an ab-

sorption vessel 7. This vessel contains a nonvolatile liquid which will absorb the vapors formed by the evacuation of the container 3. A pump 8 is indicated and serves for generating a vacuum in the container 3, a pipe leading from said pump to the pipe 6.

When the pump 8 is actuated air is drawn by suction from the container through the pipe 6, producing thereby a vacuum in the container 3 so that the liquid therein vaporizes. These vapors are absorbed in the vessel 7 whereby in a well known way the temperature of the remaining liquid in the container is reduced. On account of the circulating pipes 4 this low temperature will be communicated to the entire compartment 2 and the contents thereof, whereby the other compartments of the refrigerator also are sufficiently cooled.

The absorption vessel 7 and the pump 8 preferably are of the construction shown in Letters Patent 934545 granted jointly to me and Carl Soeren Julius Wiese.

By connecting the pipe 8 with a conduit communicating with the container 3, and with the absorption vessel 7 the pressure will be reduced in both of the vessels. Means may be provided similar to those shown in the aforesaid Letters Patent for preventing discharge of the absorption and vaporization fluid into the pump.

I claim:

An evaporator for refrigerating devices comprising a receptacle for the fluid to be evaporated and a plurality of pipes extending from the bottom of said receptacle to a point above said receptacle and returning to the top thereof, said pipes communicating at both ends with the contents of said receptacle.

Signed by me at Copenhagen, Denmark, this 30th day of January 1912.

AUGUST MARIUS KJAERSGAARD.
